UNITED STATES PATENT OFFICE.

JAMES W. CONCHAR, OF DUBUQUE, IOWA, ASSIGNOR TO THE SCHRIEBER & CONCHAR MANUFACTURING COMPANY, OF SAME PLACE.

DESIGN FOR A SAD-IRON TOP PLATE.

SPECIFICATION forming part of Design No. 27,700, dated September 28, 1897.

Application filed June 17, 1897. Serial No. 641,204. Term of patent 14 years.

To all whom it may concern:

Be it known that I, JAMES W. CONCHAR, a citizen of the United States, residing at Dubuque, in the county of Dubuque and State 5 of Iowa, have invented and produced a new and original Design for Sad-Iron Top Plates; and I do hereby declare the following to be a full, clear, and exact description of the invention.

10 This invention relates to sad-irons, and more particularly to the top plate which is serewed or otherwise attached to the sad-iron commonly known as the "Pots" sad-iron.

15 The object of the invention is to produce a new and tasteful design for this top plate to render the article more pleasing in appearance and correspondingly more attractive and salable.

20 The design is fully illustrated in the accompanying drawings, forming a part of this application, in which—

Figure 1 is a top view of the design. Fig. 2 is a bottom view of the same. Fig. 3 is a side view thereof. Fig. 4 is a central longitudinal section of the same. Fig. 5 is a transverse section in the line $x-x$ of Fig. 1.

Similar letters of reference indicate corresponding parts.

The top plate in its general outline 30 conforms to that of the sad-iron proper to which it is attached, but which is not illustrated, being no necessary part of the design. This is generally in the pointed elliptical form illustrated. In the longitudinal middle of the 35 figure is a recess B, having straight sides C, as seen from above. The sides of the plate adjacent round up from the base or bottom edge, as clearly illustrated in Figs. 1, 3, and 5. The recess itself terminates at each end 40 in a flat portion B', the middle portion of the recess B² being sunken a little below the surface of the end portions. The middle part

of the top plate A is provided with half-oval openings D, separated by a cross-bar E.

Referring to the drawings, it will be seen 45 that the top plate as seen from above, this being the only part which is visible when attached to the sad-iron, presents to the eye a general curve or rounded appearance, the sides adjacent to the middle depression not 50 only rounding and swelling out laterally, as seen in Fig. 2, but curving upwardly in the middle, as shown in Fig. 3. This upward curvature terminates near the pointed ends of the top plate, as shown in the same figure 55 and also in Fig. 1, the ends continuing in a straight line to near the apex, where they also curve down, as clearly illustrated. This smooth curved appearance of the top plate gives to it, when suitably finished, a very 60 neat and attractive appearance, greatly enhancing its commercial value.

Near each end the top plate is provided with suitable holes F F, and adjacent to these holes are small nibs G. The whole under 65 side of the top plate elsewhere is channeled out so as to conform generally to the projections and depressions on top, making the material of the whole plate practically uniform in thickness, as clearly illustrated in 70 Figs. 4 and 5.

Having thus described my invention, what I claim as new, and desire to secure by Letters Patent, is—

The design for a sad-iron top plate, substantially as described herein and illustrated in the drawings. 75

In testimony whereof I affix my signature in presence of two witnesses.

JAMES W. CONCHAR.
